UNITED STATES PATENT OFFICE.

GUY E. HORTON AND CASPAR S. WAGNER, OF AKRON, OHIO.

COLLAPSIBLE CORE.

1,136,805.

Specification of Letters Patent.

Patented Apr. 20, 1915.

Application filed October 9, 1913. Serial No. 794,238.

To all whom it may concern:

Be it known that we, GUY E. HORTON and CASPAR S. WAGNER, citizens of the United States, and residents of Akron, in the county 5 of Summit and State of Ohio, have invented a new and Improved Collapsible Core, of which the following is a full, clear, and exact description.

The invention relates to a collapsible core 10 for use in the manufacture of rubber tires; and the object thereof is to provide a simple, strong and inexpensive core which can be easily and quickly manipulated.

We attain the above object by providing a 15 core formed of a plurality of sections bound together by means of fixed and expanding rings.

The invention consists of the construction and combination of parts to be more fully 20 described hereinafter and fully set forth in the claims.

Reference is to be had to the accompanying drawings forming a part of this specification, in which like characters indicate corresponding parts in all the views and in which:

Figure 1 is an elevation of an embodiment of our invention; Fig. 2 is a section on line 2-2, Fig. 1; Fig. 3 is an enlarged section 30 of a section of a core with the binding rings; and Fig. 4 is a perspective view showing the section having the parallel ends in partially removed position, whereby the core is collapsed.

Referring to the drawings, 5 represents one of the sections of a core, the ends of which are parallel and substantially perpendicular to the transverse axis of the core. The adjacent ends of the sections 6 are 40 similar to the ends of the section 5; while the opposite ends of the sections 6 are disposed radially. The number of the sections 7 which contact with the sections 6 will vary according to the size of the core, that is, 45 there may be one or more, and the ends of said sections 7 will be necessarily disposed radially. Each of the sections is provided with a flange 8, T-shaped in cross section (see Figs. 2, 3 and 4); and one of the shoulders of each section on the same side is under cut, as shown at 9, and adapted to engage the inner, beveled surface of a ring 10. Each shoulder having the under-cut is also provided on the opposite side with an angular recess 11 adapted to be engaged by a 55 circular shoulder 12 of a split ring 13. The

split ring 13 engaging the flanges 8 of the sections forces the under-cut shoulders of the same in engagement with the beveled surface of the ring 10 when the said split ring is expanded by means of the removable pin 14 provided in the split of the ring. The shoulder 11 of the split ring forms a stop for the same, limiting its movement when forced in engagement with the sections. 60

The core is assembled as follows: The sections 6 and 7 are placed in proper position and then the section 5 is moved into place radially from the center. The ring 10 is 65 then placed in position. The split ring 13 is then made to engage the sections interiorly and the pin 14 is forced into the split of the same, thereby forcing said sections against the ring 10 and pinning them all 70 together with the said rings 10 and 13. To prevent lateral displacement of the sections, the contacting ends on one section is provided with a groove 15 engaged by a projection 16 of the other section, as shown in 75 Figs. 1 and 4. To take the core apart, the pin 14 is removed, which permits the removal of the split ring 13. By forcing the section 5 slightly toward the center, as shown in Fig. 4, the ring 10 can be removed; 80 and by removing the section 5 entirely, always in the direction toward the center, the sections 6 and 7 can be removed from a 85 formed tire.

Having thus described our invention, we 90 claim as new and desire to secure by Letters Patent:

1. In a collapsible core, a plurality of sections forming the core and each having a flange T-shape in cross section, one shoulder of which is under-cut; a fixed ring adapted 95 to engage the under-cut shoulder of the flanges; and an expanding ring adapted to engage the flanges of the sections and force said flanges against said fixed ring, one of 100 said sections having means coacting with the adjacent sections whereby the said section may be removed radially without disturbing the other sections when said expanding ring is removed, substantially as and 105 for the purpose set forth.

2. In a collapsible core, a plurality of sections forming the core and each having a flange T-shape in cross section, one shoulder of which is under-cut; a fixed ring adapted 110 to engage the under-cut shoulders of the flanges; a split ring adapted to engage the

flanges of the sections; a pin adapted to engage the split of the ring and thereby expand the same, thus forcing said section against the said fixed ring, all of said sections having means preventing the lateral displacement of the sections, and one of said sections having means coacting with the adjacent section whereby the said section can be removed radially without disturbing any 10 of the other sections forming the core when

said split ring is removed, substantially as and for the purpose set forth.

In testimony whereof we have signed our names to this specification in the presence of two subscribing witnesses.

GUY E. HORTON.
CASPAR S. WAGNER.
